APPARATUS FOR PROJECTING LIQUID JETS

Lewis G. Morris Timpson, Plainfield, N. J., assignor to Pyrene Development Corporation, a corporation of Delaware

Application December 26, 1942, Serial No. 470,125

13 Claims. (Cl. 261—116)

This invention relates to a new or improved apparatus for projecting a jet or stream of liquid and of causing said jet or stream to aspirate relatively large quantities of air or other gas. It is particularly concerned with the projection of a foam forming solution in a manner enabling it to aspirate and combine with a large volume of air for the production of fire extinguishing foam.

The present case is a continuation in part of my pending application Ser. No. 417,220, filed October 31, 1941, and is in part directed to a divisible portion of the invention disclosed in said application.

In the production of air foam, as distinguished from chemical foam, for fire extinguishing purposes, a jet of liquid is discharged into a receiver or other conduit in such a way as to aspirate air. The liquid either contains a previously introduced foam stabilizer or a material of this character is introduced simultaneously with the air. As a result the air is combined with the water and stabilizer to form a foam suitable for delivery to and use upon a fire.

An object of the invention has been to produce a jet of liquid or foam forming solution of such character or in such a manner that a relatively large amount of air will be aspirated and combined with the solution so as to form a large volume of foam. At the same time it has been an object to produce a foam of the character indicated which is of good quality and durability, without an excessive drop in the pressure available for advancing the foam and projecting it onto the fire.

Another object has been to provide an aspirating jet of the type mentioned, and under the conditions set forth, with a minimum danger of clogging the nozzles employed for the production of the jet. This is an important feature of the invention since the water from the sources of supply ordinarily available for fire extinguishing purposes frequently carries suspended particles of foreign matter of considerable size. While it is readily possible to screen out the large particles by a screen located conveniently in advance of the aspirating nozzle, it is not practicable to provide a screen to eliminate the smaller particles which are still large enough to clog an ordinary nozzle having an orifice of a diameter to provide the desired jet. Accurate construction and frequent inspection of ordinary nozzles, when used for the purpose, are required to insure proper operation.

A special feature of the invention is that the improved nozzle is capable of projecting a jet

5 in the form of a solid cone. This is particularly advantageous when the jet is permitted to aspirate air for the production of air foam, but it is advantageous also for various purposes when plain water or other liquids are projected.

A further object of the invention has been to produce a distorted vena contracta for the improved aspiration of air in the making of air foam.

10 A still further object of the invention has been to provide a simple and inexpensive nozzle construction capable of efficient operation in the manner indicated in the foregoing.

15 Other objects, features and advantages of the invention will appear from a detailed description of several illustrative embodiments of the same which will now be given in conjunction with the accompanying drawing, in which:

20 Fig. 1 is a longitudinal sectional view through approximately the center of a nozzle suitable for purposes of this invention, and

25 Fig. 2 is a similar view through a modified form of nozzle.

Referring to Fig. 1 of the drawing, numeral 15 indicates a hose, pipe or other conduit for supplying liquid under pressure to the enlarged chamber 16. The side of chamber 16 opposite pipe 15 is closed by a plate 17 having a flange 18 carrying threads to engage corresponding threads on the wall of the chamber 16. This plate may, of course, be simply welded or otherwise secured in place if desired. Plate 17 is provided with a centrally located orifice 19 having relatively sharp edges 20 inside the chamber 16. A short tube 21 is attached to the outlet side of the orifice 19 and is provided a short distance along the passageway with a number of lateral perforations or openings 22.

30 With such a construction of nozzle, the liquid approaching the corners 20 to pass out through the orifice 19 is largely moving laterally inward. Because of this factor, the smallest diameter of the liquid jet passing out through orifice 19 will be substantially smaller than the actual diameter of the orifice 19. This liquid jet will then tend to spread out as it moves away from the orifice until by the time it reaches the outer end of the tube 21, it will again be substantially the same diameter as the diameter of the orifice 19.

35 If the perforations 22 in the tube are not employed, the liquid jet passing through the orifice 19 will tend to form a vacuum between the outer surface of the jet and the inner surface of the tube 21, thus causing the liquid to conform more closely to the walls of the tube 21 and producing

only normal turbulence. By introducing the perforations 22 at a distance from the orifice equal to approximately the diameter of the orifice 19, however, the vacuum is broken, some air is drawn into the tube 21 and the liquid passing out through the tube 21 is highly turbulent, and, in fact, is practically reduced to a solid cone of spray. The tube 21 however, should not be much longer than about three times the diameter of the orifice 19 in order to produce this effect.

The enlargement of the chamber 16 aids in producing this effect by causing the liquid flowing through the pipe 15 to reduce its forward speed and move out laterally into the enlarged chamber 16. This liquid then has to flow laterally inward towards the orifice 19 in order to pass out through it. As a practical matter, it is desirable to have a chamber 16 which is in diameter at least eight times the diameter of the orifice 19. A chamber which is ten times the diameter of orifice 19 in size is satisfactory for most purposes. The orifice 19 is illustrated as circular in cross section but may, of course, be made square, triangular, or of any other suitable shape.

In Fig. 2 there is disclosed a modified construction embodying the same broad principles as the construction illustrated in Fig. 1 but different specifically in form and operation. Water or other liquid, such as a foam producing solution, i. e., water containing a foam stabilizer, may be delivered through a pipe or hose or other conduit 23 into the interior of a nozzle indicated generally at 24. This nozzle may have a screw-threaded flange 25 with internal threads adapted to engage external threads at the end of the pipe or hose line 23. A rubber washer 25a, or the like, may be provided between the end of the conduit 23 and a shoulder 26 within a nozzle. The water or other liquid delivered through the pipe 23 is passed into a main chamber 27 within the nozzle, the first portion of this chamber being of slightly smaller cross section than the delivery conduit. As a result of this, a part of the stream will be directed against the flat shoulder 26 and will be deflected inwardly by the latter and forced to mingle with the rest of the stream which passes directly into the chamber 27. In this way a substantial amount of interference and turbulence is initiated at the periphery of the stream. This effect is increased by the provision of a sharp edge 28 along the line of intersection between the shoulder 26 and the chamber 27. Toward its outer end the chamber 27 is enlarged somewhat, as indicated at 29, a smooth, well rounded shoulder 30 being provided between the two portions of the chamber. The stream thus expands or spreads freely into the enlarged portion 29 but is subsequently directed inwardly toward the axis of the chamber by an end wall 31.

Fitted within a screw-threaded aperture 32 in the end wall is a discharge element 33 having screw-threaded engagement with the end wall and provided with a radially extending flange 34 which serves to clamp a gasket or washer 35 against the outer face of the wall 31. A plurality of grooves 36 may be provided in the outer face of the discharge element for the receipt of an appropriate wrench to tighten the element in place. At its inner end the discharge element is provided with an inwardly projecting tubular portion 37 extending axially into the portion 29 of the chamber. The inner end of this tubular extension is preferably chamfered, as indicated at 38, but it is provided with a sharp corner 39

at the entrance to a passage 40 which extends through the tubular portion. A series of apertures or small openings 41 is provided around the tubular portion, these extending, preferably radially through the wall of the tube. At its base the tubular portion 37 may suitably be flared outwardly to provide a frusto-conical section 42 which merges into the main inner surface 43 of the discharge element, this being flush with the inner surface of the wall 31. On its outer face the element 33 is provided with a frusto-conical discharge orifice 44. This forms an outwardly flaring extension of the passage 40 beginning slightly beyond the apertures 41.

As indicated by the arrows, the flow of the water or other liquid within the portion 29 of the chamber is such that a part is directed radially inwardly through the openings 41 into the interior of the tubular extension 37. Another part moving radially inward adjacent the inner end of the tubular extension 37 merges with a part of the stream which passes axially into the tubular extension and thus provides the effect described in connection with Fig. 1. Due to the sharp corner 39 and the merging of the different parts of the stream in the manner indicated, the liquid entering the tubular extension assumes a cross section less than the internal diameter of this extension up to the point at which it is met by the water flowing inwardly through the openings 41. From this point on the tube is completely filled and as the water reaches the conical discharge orifice 44, it expands outwardly and forms a substantially solid, conical spray. This conical spray is excellently suited for the incorporation of air to form foam, in the manner hereinbefore indicated. For this purpose the nozzle may be arranged to discharge into a suitable receiver, a portion of which is shown at 45 in Figure 2. This receiver may suitably be of the type illustrated in my pending application, Ser. No. 417,220, above mentioned. A large quantity of air may be readily aspirated in this manner and combined with the liquid, which in this case should contain a suitable quantity of an appropriate foam stabilizer. The foam stabilizer may, if desired, be incorporated by aspiration in advance of the nozzle 24, induced by the flow of the water under pressure derived from a hydrant or the like, or it may be introduced in advance of the pump which applies the pressure to the stream. It will be understood that the form of nozzle disclosed in Fig. 1 may also be used in conjunction with a receiver in the same manner to produce air foam.

Due to the tendency of the stream to assume a cross section of less diameter than the passage 19 in Fig. 1 or passage 40 in Fig. 2, it will be seen that these passages may be formed of larger diameter than an ordinary discharge orifice adapted to discharge a predetermined volume of liquid. Accordingly, relatively large particles of foreign matter may be carried along in the stream without danger of clogging the passage. Moreover, due to the interaction of the conflicting streams which are brought together at the entrance to the tubular extension and within the latter, a high degree of dispersion of the projected spray results. When this is used for the production of air foam a large volume of air is readily incorporated and an excellent, durable foam is formed. This is accomplished, furthermore, without excessive retardation of the forward movement of the stream.

While the invention is not restricted to the em-

placement of specific dimensions in the construction of the improved nozzle, a typical unit which has been found quite satisfactory has been formed as follows: Referring to Fig. 2, assuming the pipe 23 has an outside diameter of about $2\frac{1}{2}$ inches, the chamber 27 has an inside diameter of about $1\frac{1}{8}$ inches in the initial portion and about 2 inches in the enlarged portion 29. The threaded opening 32 is suitably of about $\frac{7}{8}$ inch diameter while tubular extension 37 is $\frac{1}{4}$ inch long, has an internal diameter of .187 inch and has a series of four apertures 41 of $\frac{1}{16}$ inch diameter. These apertures are positioned with their axes about $\frac{1}{8}$ of an inch from the inlet end of the tubular extension. The angle of the frusto-conical discharge orifice 44 may suitably be about 60°.

As indicated, the precise dimensions of the various elements may be varied to suit particular requirements and so also the relationship between the various dimensions may be varied to a certain extent without departing from the general principles and scope of the invention. In general, however, it may be stated that the diameter of the passage 40 should not be more than about one-eighth, and preferably not more than one-tenth, of the diameter of the portion 29 of the chamber. The ratio of the cross-sectional areas of the portion 29 and the passage 40 of the chamber should, accordingly, be preferably about a hundred to one although it may be as low as fifty to one, or under some circumstances even less. The distance from the inlet end of the passage 40 to the plane through the axes of the apertures 41 should be at least equal to the diameter of the passage 40.

Various changes, in addition to those suggested above, may be made in the construction, arrangement and general relationship of the parts without departing from the invention. The terms and expressions used herein have been used as terms of description and not of limitation.

What I claim is:

1. A nozzle for projecting a jet of liquid comprising a chamber of relatively large diameter arranged to receive a stream of liquid under pressure, discharge means in a wall of said chamber, said means having a passage therethrough of a diameter not more than about one-eighth that of said chamber, said passage having a sharp edge at its inlet, and said means having apertures communicating with said passage at an angle to the axis thereof and intermediate the ends thereof.

2. A nozzle for projecting a jet of liquid comprising a chamber of relatively large diameter arranged to receive a stream of liquid under pressure, discharge means in a wall of said chamber, said means having a passage therethrough of a diameter not more than about one-eighth that of said chamber, said passage having a sharp edge at its inlet, and said means having apertures providing additional inter-communication between said chamber and said passage intermediate the ends of the latter.

3. A nozzle for projecting a jet of liquid comprising a chamber of relatively large diameter arranged to receive a stream of liquid under pressure, discharge means in a wall of said chamber, said means having a passage therethrough of substantially less diameter than said chamber, said passage having a sharp edge at its inlet, and said means having apertures providing additional inter-communication between said chamber and said passage intermediate the ends of the latter, said apertures leading into said passage at an angle to the axis thereof.

4. A nozzle for projecting a jet of liquid comprising a chamber of relatively large diameter arranged to receive a stream of liquid under pressure, discharge means in a wall of said chamber, 5 said means having a passage therethrough of substantially less diameter than said chamber, said passage having a sharp edge at its inlet, and said means having radially extending passages within said chamber communicating directly with said first-mentioned passage for introducing additional liquid from said chamber into the stream flowing through the passage.

5. Apparatus for producing fire extinguishing foam which comprises a receiver, a nozzle for projecting a jet of foam-forming liquid into said receiver, said nozzle being so arranged in relation to said receiver as to aspirate air upon the projection of said liquid into the receiver, said nozzle having an enlarged chamber through which said liquid is passed and a discharge tube connected with a wall of said chamber and forming an outlet therefrom, said tube having a sharp entrance edge and having apertures extending through its wall from the exterior to the interior thereof intermediate its ends in a region at a distance from the inlet end of said tube about equal to the diameter of the passage through said tube.

6. Apparatus for producing fire extinguishing foam which comprises a receiver, a nozzle for projecting a jet of foam-forming liquid into said receiver, said nozzle being so arranged in relation to said receiver as to aspirate air upon the projection of said liquid into the receiver, said nozzle having an enlarged chamber through which said liquid is passed and a discharge tube connected with a wall of said chamber and extending inwardly into the chamber, said tube having a sharp entrance edge and having apertures providing additional inter-communication between said chamber and the interior of said tube.

7. Apparatus for producing fire extinguishing foam which comprises a receiver, a nozzle for projecting a jet of foam-forming liquid into said receiver, said nozzle being so arranged in relation to said receiver as to aspirate air upon the projection of said liquid into the receiver, said nozzle having an enlarged chamber through which said liquid is passed and a discharge tube connected with a wall of said chamber and forming an outlet therefrom, said tube having a passage therethrough of a diameter not exceeding one-eighth that of said chamber, the entrance edge of the passage through said tube being sharp, and said tube having perforations in the wall thereof.

8. Apparatus for producing fire extinguishing foam which comprises a receiver, a nozzle for projecting a jet of foam-forming liquid into said receiver, said nozzle being so arranged in relation to said receiver as to aspirate air upon the projection of said liquid into the receiver, said nozzle having an enlarged chamber through which said liquid is passed and a discharge tube connected with a wall of said chamber and forming an outlet therefrom, said tube extending into said chamber and having a passage therethrough of a diameter not exceeding one-eighth that of said chamber, the entrance edge of the passage through said tube being sharp, and said tube having perforations in the wall thereof providing intercommunication between said chamber and said passage.

9. Apparatus for producing fire extinguishing foam which comprises a receiver, a nozzle for projecting a jet of foam-forming liquid into said receiver, said nozzle being so arranged in relation to said receiver as to aspirate air upon the pro-

jection of said liquid into the receiver, said nozzle having a chamber through which said liquid is passed and a discharge tube connected with a wall of said chamber and having a passage forming an outlet therefrom, said chamber being enlarged adjacent said wall, said passage through said tube having a sharp entrance edge and having apertures extending through its wall from the exterior to the interior thereof intermediate its ends, said apertures being arranged to break the vacuum in said tube at a short distance from the inlet thereof.

10. Apparatus for producing fire extinguishing foam which comprises a receiver, a nozzle for projecting a jet of foam-forming liquid into said receiver, said nozzle being so arranged in relation to said receiver as to aspirate air upon the projection of said liquid into the receiver, said nozzle having a chamber through which said liquid is passed and a discharge tube in the end wall of said chamber extending into the chamber, said chamber being enlarged in the region of said tube, the cross-sectional area of the enlarged portion of the chamber being at least fifty times that of the interior of said tube, said tube having a sharp edge at its entrance and being apertured some distance from the end thereof to provide additional inter-communication between said chamber and the interior of said tube.

11. A nozzle for projecting a jet of liquid comprising a chambered member adapted to be applied to a liquid conduit, discharge means in the end of said member, said means having a tubular portion extending into the chamber within said member, said tubular portion having a passage 30 therethrough of not more than one-eighth the diameter of said chamber, said passage being pro-

vided with a sharp edge at its inlet end, and openings through the wall of said tubular portion at points spaced from the inlet end of said passage a distance substantially equal to the diameter of said passage.

5. 12. A nozzle for projecting a jet of liquid comprising a chambered member adapted to be applied to a liquid conduit, discharge means in the end of said member, said means having a tubular portion extending into the chamber within said member, said tubular portion having a passage therethrough of not more than one-eighth the diameter of said chamber, said passage being provided with a sharp edge at its inlet end, and openings through the wall of said tubular portion at points spaced from the inlet end of said passage a distance substantially equal to the diameter of said passage, said discharge means having an outwardly flared discharge orifice axially aligned with said passage.

15. 13. A nozzle for projecting a jet of liquid comprising a chambered member adapted to be applied to a liquid conduit, discharge means in the end of said member, said means having a tubular portion extending into the chamber within said member, said chamber being enlarged in the region around said tubular portion, said tubular portion having a passage therethrough of not more than one-eighth the diameter of the enlarged part of said chamber, said passage being provided with a sharp edge at its inlet end, and openings through the wall of said tubular portion at points spaced from the inlet end of said passage a distance substantially equal to the diameter of said passage.

LEWIS G. MORRIS TIMPSON.
